SOFT SIDE SUITCASE

Anthony N. D'Elia, Riverdale, and Edward M. Stolarz,
Yorktown Heights, N.Y., assignors to Reliable Luggage,
Inc., West Pittsburg, Pa., a corporation of Pennsylvania

Filed Nov. 14, 1967, Ser. No. 9,403

Term of patent 14 years

Int. Cl. D3—01

U.S. Cl. D87—5

FIG. 1

FIG. 2

FIG. 3

FIG. 4

FIG. 5

FIG. 6

FIG. 1 is a front elevational view of a soft side suitcase embodying our new design;

FIG. 2 is a side elevational view thereof;

FIG. 3 is a top plan view thereof;

FIG. 4 is a bottom plan view thereof;

FIG. 5 is a rear elevational view thereof; and,

FIG. 6 is a side elevational view of the opposite side of that shown in FIG. 2.

We claim:

The ornamental design for a soft side suitcase, as shown.
